Primary Examiner — Mark A Goodwin*Assistant Examiner* — Benjamin M Weeks(74) *Attorney, Agent, or Firm* — Maginot Moore & Beck LLP(57) **CLAIM**

The ornamental design for a garment with side pocket, as shown and described.

DESCRIPTION

FIG. 1 shows a right side elevational view of a first embodiment of a garment with side pocket showing my new design; FIG. 2 shows a front elevational view thereof; and FIG. 3 shows a rear elevational view thereof.

FIG. 4 shows a left side elevational view of a second embodiment of a garment with side pocket showing my new design;

FIG. 5 shows a front elevational view thereof; and FIG. 6 shows a rear elevational view thereof.

FIG. 7 shows a right elevational view of a third embodiment of a garment with side pocket showing my new design; FIG. 8 shows a left elevational view thereof;

FIG. 9 shows a front elevational view thereof; and FIG. 10 shows a rear elevational view thereof.

The broken lines shown in the drawings/figures illustrate environmental matter and form no part of the claimed design.

1 Claim, 10 Drawing Sheets(56)
